BERTRAND B. KAHN, OF CINCINNATI, OHIO, ASSIGNOR TO THE ESTATE STOVE COMPANY, OF HAMILTON, OHIO, A CORPORATION OF OHIO.

HEATING APPLIANCE.

Application filed October 30, 1925. Serial No. 65,769.

The present invention relates to heating appliances and more particularly to heating appliances of the character which are adapted to be placed in the room to be heated.

5 One of the principal objects of the invention is to provide a radiant heater so constructed that none of the products of combustion can escape into the room.

10 Another object is to provide a radiant heater so constructed as to facilitate circulation of air over certain parts thereof whereby to supplement radiation by convection currents.

15 Still another object of the invention is the construction of a radiant heater having provisions for humidifying the air of the room in which it is placed.

20 These and other objects will be apparent from the following description taken in connection with the accompanying drawings in which:

25 Fig. 1 is a front elevation of a heating appliance constructed in accordance with the present invention;

30 Fig. 2 is a plan view of Fig. 1, parts being broken away and others being shown in section to illustrate features of the invention;

35 Fig. 3 is a vertical section taken on the line 3—3 of Fig. 1; and

40 Fig. 4 is a vertical section taken on the line 4—4 of Fig. 3.

In the drawings, which illustrate a portable radiant heater adapted to be placed in the room to be heated, 20 denotes the base portion upon which is carried a combustion chamber 21 which, as best shown in Fig. 2, is an elongated chamber extending across the front of the heater. The shape and proportions of the combustion chamber are of course subject to variation, but in the preferred form herein illustrated, the combustion chamber is of a generally rectangular section (see Fig. 2), the rear wall 22 and the end walls 23 being cast integral and secured to a front wall 24 which is provided with an opening 25 through which heat energy from the refractory radiating elements 26 may radiate in a forward direction.

45 The refractory radiating elements 26 are mounted within the combustion chamber 21 and preferably are of such dimensions to present in effect a composite element of substantially the same extent as the opening 25. As best shown in Fig. 3, each radiating element is hollow and is supported in any suit-

able manner from the lower part of the combustion chamber. The combustion chamber 21 is provided with an opening in its lower wall underneath the radiating elements 26 to receive a burner 29, which burner may be connected by means of a pipe 30 with a suitable source of fuel supply. Any suitable fuel may be employed for heating the radiating elements 26 by providing suitable burners, but the burner herein illustrated is one intended for the use of gaseous fuel such as natural gas or the like. The burner is provided with a gas valve 31 for controlling the flow of gas to the burner and a mixing device 32 by which air may be admixed with the fuel to produce a combustible mixture, as is well understood in the art. Burning of the combustible mixture at the openings 33 serves to heat the refractory radiating elements 26 to incandescence thereby resulting in the radiation of heat energy therefrom. Preferably each radiating element is provided with groups of slotted apertures 35 through its front and rear walls, the apertures being so spaced as to provide bars of refractory material between them, which are heated by the products of combustion, such bars being narrow and adapted to readily absorb heat from the hot gases coming from the burner. The arrangement of slotted apertures and bars here illustrated while adapted for efficiently absorbing heat from the hot gases and quickly bringing the radiating element to a condition of incandescence, is one which presents a pleasing appearance to the eye when viewed through the radiating opening 25.

45 The radiating opening 25 at the front of the combustion chamber is preferably closed by a window 38 which serves the double function of preventing the escape of the products of combustion from the combustion chamber 21 through the opening 25 thereby vitiating the air of the room, and also preventing the entrance of cool air through the opening 25 into contact with the radiating element 26. The importance of preventing chilling of the radiating element by the entrance of cool air will be appreciated, when it is understood that the effectiveness of a radiating element, and the amount of radiation therefrom varies approximately as the fourth power of the absolute temperature differential between the element and the body to be heated. The material of the window may be of glass or other material which is transparent to radiant

energy and this permits the passage of radiant energy therethrough, and the window may be carried in a hinged frame 39 having suitable hinges indicated at 39' and having a locking handle 40 by which the frame may be secured in position.

A secondary radiator 45 which is of a flat construction is secured to the rear wall of the combustion chamber, the wall of the secondary radiator being preferably spaced from the rear wall of the combustion chamber to provide air passages 46 therebetween for the circulation of air over the outer surfaces of the combustion chamber and of the secondary radiator whereby such air is heated by convection. The secondary radiator which may be very simply cast in two parts, as best shown in Fig. 3, is provided with suitable partitions or dividing walls 47 which form with the outer walls of the secondary radiator, tortuous passages 48 and 49 adapted to be connected with the interior of the combustion chamber and to receive the hot products of combustion therefrom. These dividing walls are preferably corrugated and provided with a plurality of openings or passages 50 through which the products of combustion may pass. In the absence of such openings it is sometimes found that there is too much resistance to draft through the device during the initial stage of use, before the flue and other parts have heated up, so as to interfere with the draft and thus give undesirable operating results. The combustion chamber and the secondary radiator passages are connected at their upper parts through a central opening 52 and the lateral openings 53. The passages within the secondary radiator are provided at a point remote from the inlet openings 52 and 53 with a flue collar 54 through which the products of combustion may be conducted to a flue after they have traversed the tortuous passages of the secondary radiator 45. This radiator is of course heated by radiation from the radiant elements as well as by the hot products of combustion passing thereover.

A water pan 55 is provided near the combustion chamber, which pan has a filling spout or extension 56 extending to the outside of the heater for convenience in filling. The pan is adapted to receive water for the humidification of the air circulating over the outer surfaces of the combustion chamber and of the secondary radiator.

An enclosing casing 60 may be secured to the front portion 24 of the heater and to the base 20 for the purpose of providing air passages about the combustion chamber and the secondary radiator to facilitate the passage of convection currents over these parts. The enclosing casing of course also has the advantage that it forms a protection to prevent children and others from touching the hot parts of the combustion chamber and the secondary radiator. The upper part of the en-

closing casing 60 may consist of a grating or cover 61 of a somewhat ornamental nature harmonizing with the design of the radiant heater taken as a whole, but having suitable apertures 62 for the passage of the heated air, the solid parts of the grating of course serving to facilitate the mixture of heated air coming from various parts of the heater.

From the foregoing it will be apparent that the present invention provides an efficient portable heater which may be placed in a room for heating the same. The enclosure of the radiating element and the protection provided against the passage of cool air currents thereover, enables the radiating element to be maintained at a uniformly high temperature thereby increasing the effectiveness of heating through radiation from the radiating element. In addition to the heating effected by radiation through the opening there is a general heating of the air in the room through convection by reason of the provision of the secondary radiator and the enclosing casing, which latter is arranged to facilitate the passage of air currents over the heated exterior surfaces of the combustion chamber and of the secondary radiator, as indicated by the plain arrows in Figs. 2, 3 and 4. A further advantage of the present invention is that the products of combustion are at all times confined and can not escape into the air circulating system, as will be apparent from Figs. 2, 3 and 4 in which the flow of the products of combustion is indicated by the feathered arrows. By virtue of the secondary radiator with its tortuous passages most of the sensible heat is extracted from the products of combustion so that the temperature of these products is extremely low as they pass through the flue collar 54, and consequently a high efficiency is obtained for the heater.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A portable gas burning combined radiation and circulation type heater adapted to be used in a room, comprising a gas burner, a casing forming a combustion chamber enclosing said burner, radiant means within said combustion chamber and positioned to be heated by the gas burning at said burner, a passage connected to said combustion chamber through which the heated products of combustion pass to a flue, and an air circulating pipe positioned in direct heat-transferring impinging relation with the gases burning within said combustion chamber, said pipe having an air-inlet opening into

the bottom thereof and a vertically arranged heated air discharge opening in the top thereof, whereby the heated air is discharged upwardly at high velocity to effect circulation 5 of the air within the room.

2. A portable gas burning radiation and circulation type heater adapted to be used in a room, comprising a gas burner, a casing forming a combustion chamber enclosing said burner, radiant means within said combustion chamber and positioned to be heated by the gas burning at said burner, a passage connected to said combustion chamber through which the heated products of combustion pass 10 to a flue, an air-circulating pipe positioned in direct heat-transferring impinging relation with the gases burning within said chamber, and means for causing the hot products of combustion within said passage to follow a 15 tortuous path to effect increased heating of the walls of the said air-circulating pipe, said air-circulating pipe having an unrestricted inlet opening into the bottom thereof and a vertically arranged heated air discharge opening at the top thereof, whereby the heated air passing through the said pipe is discharged freely upwardly at high 20 velocity to effect circulation of the air within the room.

3. A portable gas burning combined radiation and circulation type heater adapted to be used in a room, comprising a gas burner, a casing forming a combustion chamber enclosing said burner, radiant means within said combustion chamber and positioned to be heated by the gas burning at the said burner, a passage connected to said combustion chamber through which the heated products of combustion pass to the flue, an air-circulating pipe in direct heat-impinging relation with the heated products of combustion within said passage, and a casing around the sides of said passage walls and the said combustion chamber and spaced therefrom to provide an air-circulating channel outside of the walls of the said passage, the air-circulating pipe and said surrounding air-circulating channel being positioned in direct heat-transferring impinging relation with the said 40 hot products of combustion through the intermediary of the walls of said combustion chamber and said passage, the said air pipe and the said channel each having an air-inlet opening into the bottom thereof and each having a vertically arranged heated air discharge opening at the top thereof, whereby the air heated within the said pipe and channel is discharged vertically upwardly at high velocity to effect circulation of the air within the room.

4. A portable gas burning combined radiation and circulation type heater adapted to be used in a room, comprising a gas burner, a casing forming a combustion chamber enclosing said burner, a hollow open bottom

radiant within said combustion chamber and positioned over and around the gas burning at said burner, a passage connected to said combustion chamber through which the heated products of combustion pass to the 70 flue, and a vertically arranged hot air-circulating passage positioned in heat-transferring relation with the said first-named passage, said hot air-circulating passage having an unrestricted vertical discharge, whereby the air heated within said air-circulating passage is discharged upwardly at high velocity to effect circulation of the air within the room.

5. A portable gas burning combined radiation and circulation type heater adapted to be used in a room, comprising a gas burner, a casing forming a combustion chamber enclosing said burner, radiant means within said combustion chamber and positioned to be heated by the gas burning at the said burner, a passage connected to said combustion chamber through which the heated products of combustion pass to the flue, a vertically arranged air-circulating pipe indirect 80 heat-impinging relation with the heated products of combustion within said passage, and a casing around the said passage walls and the said combustion chamber and spaced therefrom to provide a vertically arranged 90 air-circulating channel outside of the walls of said passage, the air-circulating pipe and said surrounding air-circulating channel being positioned in heat-transferring relation with the said hot products of combustion through the intermediary of the walls of said passage, the said air pipe and the said channel each having an air-inlet opening into the bottom thereof and each having a vertically arranged heated air discharge 100 opening at the top thereof, whereby the air heated within the said pipe and channel is discharged vertically upwardly at high velocity to effect circulation of the air within the room.

6. A portable gas burning combined radiation and circulation type heater adapted to be used in a room, comprising a gas burner, a casing forming a combustion chamber enclosing said burner, hollow open bottom radiant means within said combustion chamber and positioned over and around the gas burning at the said burner, a passage connected to said combustion chamber through which the heated products of combustion pass to the flue, an air-circulating pipe within the walls of said passage, and a casing around the sides of the said passage walls and the said combustion chamber and spaced therefrom to provide an air-circulating channel outside of the walls of said passage, the air-circulating pipe and said surrounding air-circulating channel being positioned in heat-transferring relation with the said hot products of combustion through the intermediary of the walls 110 120 125 130

of said passage, and baffle means arranged within said passage to cause said hot products of combustion to follow a tortuous path to effect increased heating of the walls of said passage, the said air pipe and the said channel each having an unrestricted air-inlet opening into the bottom thereof and each having a vertically arranged heated air discharge opening at the top thereof, whereby the air heated within the said pipe and channel is discharged vertically upwardly at high velocity to effect circulation of the air within the room.

7. A portable gas burning combined radiating and circulating type heater adapted to be used in a room, comprising a casing having side walls and a back wall, the top of the heater providing an air-discharge opening providing for upward discharge of heated air at high velocity from the heater, a base plate on which the said side walls of the casing are mounted, with the back wall of the casing overhanging the rear of the base plate to provide for upward passage of air into the casing, a combustion chamber member on said base plate spaced from the back wall and side walls of the casing to provide an air-circulating passage therebetween, a radiant energy transparent closure for the front of the casing to provide a closed combustion chamber, a gas burner on said base plate, radiant means above the burner, and a passage for hot products of combustion provided between the combustion chamber member and the back wall of the casing.

8. A portable gas burning combined radiating and circulating type heater adapted to be used in a room, comprising a casing having side walls, a back wall, and a top wall, said top wall having air-discharge openings providing for upward discharge of heated air at high velocity from the heater, a base plate on which the said side walls of the casing are mounted, with the back wall of the casing overhanging the rear of the base plate to provide of unrestricted upward passage of air into the casing, supporting feet on said

base plate, a combustion chamber member on said base plate spaced from the back wall and side walls of the casing to provide an air-circulating passage therebetween, a radiant energy transparent closure for the front of the casing to provide a closed combustion chamber, a gas burner on said base plate, hollow radiant means above the burner within which the gas is adapted to burn, and a passage for hot products of combustion having a flue opening at one end and connecting with the top of the combustion chamber at its other end, said last passage being provided between the combustion chamber member and the back wall of the casing.

9. A portable combined radiation and circulating gas burning heater comprising a closed combustion chamber having an opening in the front wall thereof, means transparent to radiant energy for closing said opening, a series of vertically extending hollow refractory radiating elements arranged side by side within said combustion chamber and adapted to radiate heat forwardly from said opening, means within the combustion chamber for heating said elements, a casing spaced from the walls of said combustion chamber and providing an air passage with substantially unrestricted inlet and outlet openings at the bottom and top of the heater for the circulation of air whereby to heat the air by convection, a flattened secondary radiator supported adjacent to but spaced from the rear wall of said combustion chamber and within said casing to provide a passage therebetween for the circulation of air to be heated by convection, said secondary radiator having passages therein communicating at a plurality of points with the interior of the combustion chamber for receiving hot products of combustion therefrom, and said secondary radiator having an outlet opening adapted to be connected with a flue.

In testimony whereof I hereto affix my signature.

BERTRAND B. KAHN.
